GEORGE JOHN MEYER AND EDWARD ALBERT TISCHER, OF MILWAUKEE, WISCONSIN,
ASSIGNORS TO GEORGE J. MEYER MANUFACTURING COMPANY, OF MILWAUKEE,
WISCONSIN, A CORPORATION OF WISCONSIN.

EXPANDING BRUSH.

Application filed April 25, 1921. Serial No. 464,420.

To all whom it may concern:

Be it known that we, GEORGE J. MEYER and EDWARD A. TISCHER, citizens of the United States, and residents of Milwaukee, in the county of Milwaukee and State of Wisconsin, have invented new and useful Improvements in Expanding Brushes, of which the following is a description, reference being had to the accompanying drawings, which are a part of this specification.

The invention relates to expanding brushes for washing bottles or other containers.

One of the objects of the invention is to provide a brush having backs in which the bristles may be wire bound and readily renewed.

A further object of the invention is to provide a brush having separable sections readily removable from their support.

The invention further consists in the several features hereinafter set forth and more particularly defined by claims at the conclusion hereof.

In the drawings: Fig. 1 is a vertical sectional view of a device embodying the invention; Fig. 2 is a detail view of the brush in an open condition; Fig. 3 is a detail section taken on the line 3—3 of Fig. 1; Fig. 4 is a side view of the device, the bristles being omitted.

In the drawings, the numeral 4 designates a pair of complementary brush backs, each having a semicylindrical body portion 5 and a shank portion 6 provided with laterally extending ears 7 offset from the axis of rotation of the device.

The backs 4 are mounted in a holder 8 composed of semi-cylindrical sections 9 hingedly connected together at their lower ends, as by a pin 10 mounted in one section and passing through an ear 11 in the other section. These sections have complementary recesses forming a recess 12 with pockets 13 adjacent this recess. The shank portions 6 of the backs 4 fit in the recess 12 and the ears 7 in the pockets 13.

The body portions 5 of the backs have inner surfaces 14 extending at an angle to the inner surface 15 of shank portions 6 thereof and are provided with recesses 16 on their inner sides.

Bristles 17 are secured to each of the backs by wires 18, the bristles being fastened by the wire bound or drawn method whereby

the wire passes through the looped end 19 of each set of bristles which are drawn into openings 20 in the backs, the wire being passed through smaller openings 21 communicating with the openings 20 and the recess 16. This construction is made possible by forming the backs of separable sections and by it worn bristles may be readily replaced without the necessity of furnishing a complete new brush.

The holder 8 has a threaded end 22 fitting in a threaded socket 23 forming part of a conduit for introducing washing liquid into the bottle 24, or other container, to be washed, the joints between sections 9 and between the backs being loose enough to permit the ready passage of water from the conduit into the bottle. This threaded connection between the holder and socket clamps the sections 9 together and holds the backs in place.

As here shown the conduit is formed by a pipe 25 receiving liquid from any suitable source of supply and reinforced by an outer tube 26. This pipe structure which supports the brush is movable into and out of the bottle and rotated in the usual manner. The bottle 24 is disposed within a holder 27 in inverted position and its mouth rests upon the upper end 28 of a drain pipe 29.

The weight of the backs 4 above their pivots normally acts to hold the body portions thereof separated, as shown in Fig. 1, and the action of centrifugal force upon these backs when the brush is rotated holds them in this position and exerts pressure upon the bristles to keep them in contact with the interior of the bottle. In order to relieve the shank portions 6 of shearing or torsional strains set up by the rapid rotation of the brush, a tongue 30 is provided on each back adapted to fit in a recess 31 in the upper end of the holder when the body portions of the brush members are separated. When the brush is passed through the neck of the bottle the inner flat surfaces 14 of the members 4 are moved into contact with or close to each other, the pressure of the bristles upon the bottle automatically moving the members to this position so that the body portions of the members 4 do not interfere with the entry of the brush into the bottle. When the brush is rotated and the body portions 6 assume an inclined

position with respect to the axis of rotation of the brush the surfaces 15 of the shank portions come close together but do not interfere with this spreading action which is limited by the tongues 30 acting as stops. On the removal of the holder 8 from its support it can be opened up on its hinge connection, as shown in Fig. 2, whereupon the backs 4 may be lifted out of the sections 10 of the holder.

We desire it to be understood that this invention is not to be limited to any specific form or arrangement of parts except in so far as such limitations are specified in the 15 claims.

What we claim as our invention is:

1. In an expanding brush, the combination of a rotatable brush holder having a central cavity opening towards its end, a 20 pair of complementary brush backs having shank portions pivoted to the brush holder within the cavity to swing freely outward under centrifugal force to limit positions determined by engagement with opposite 25 walls of said cavity, said shanks being removably connected to said holder and said brush backs having recesses and brush tuft openings for wire-drawn tufts communicating with said recesses.
2. In an expanding brush, the combination of a rotatable brush holder having separable recessed sections, and a pair of complementary brush backs having bristle-holding portions and shank portions provided 30 with pivots axially spaced removably seated in the recessed portions of said sections in a plane normal to the axis of the brush holder and permitting the bristle-holding portions to swing outwardly, said backs 35 with their pivots being directly removable from said holder when the sections are separated.
3. In an expanding brush, the combination of a rotatable brush holder having separable recessed sections, a pair of complementary brush backs having bristle-holding portions and shanks provided with laterally extending ears pivotally mounted in the recessed portions of said section in a plane 40 normal to the axis of the brush holder and permitting the bristle-holding portions to swing outwardly.
4. In an expanding brush, the combination of a brush holder having separable recessed sections, a pair of complementary brush backs having bristle-holding portions and shank portions provided with pivots removably seated in the recessed portions of 45 said sections and permitting the bristle-holding portions to swing outwardly, and means for relieving said shank portions of strains due to rotation, said backs being directly removable from said holder when the sections are separated.

5. In an expanding brush, the combination of a brush holder having separable recessed sections, a pair of complementary brush backs having bristle-holding portions and shank portions provided with pivots removably seated in the recessed portions of 50 said sections and permitting the bristle-holding portions to swing outwardly, and having tongue and groove connections with the sections of said holder for relieving said shank portions of strains due to rotation, 55 said backs being directly removable from said holder when the sections are separated.

6. In an expanding brush, the combination of a brush holder having separable recessed sections hingedly connected together 60 and having a continuous thread at its lower end, a socket member into which the threaded end fits and by which the sections are held clamped together, and a pair of complementary brush backs having bristle-holding portions and shanks provided with laterally extending ears pivotally seated in the recessed portions of 65 said sections and permitting the bristle-holding portions to swing outwardly, said shanks being directly removable from the sections of the holder 70 when the holder is disconnected from said socket.

7. In an expanding brush, the combination of a brush holder having separable recessed sections and having a continuous thread at its lower end, a socket member into which the threaded end fits and by which the sections are held clamped together, a pair of complementary brush backs 75 having bristle-holding portions and shanks provided with laterally extending ears pivotally seated in the recessed portions of said sections and permitting the bristle-holding portions to swing outwardly, and an interlocking connection between said backs and the sides of said holder when the backs are 80 in expanded position to relieve said shanks of strains due to rotation, said shanks being directly removable from the sections of the holder 85 when the holder is disconnected from said socket.

8. In an expanding bottle-washing brush, the combination of a separable holder, a pair of complementary brush backs having 90 semicylindrical tuft-holding portions and shank portions extending into the holder and pivoted thereto to swing freely outward within certain limits, said tuft-holding portions having recesses and brush tuft-receiving openings for wire-drawn brush tufts 95 communicating with said recesses.

In testimony whereof, we affix our signatures, in presence of a witness.

GEORGE JOHN MEYER.
EDWARD ALBERT TISCHER.
